BUILDING ELEMENT

William Henrichsen, Long Island City, N. Y.

Application March 20, 1948, Serial No. 15,989

2 Claims. (Cl. 20—4)

1

This invention relates to a building element and more particularly to a building element which can interlock with similar elements forming a strong connection between the elements.

It is well known to interlock building elements such as blocks of wood, tiles and stone blocks. The conventional means of forming an interlocking joint is to form a tongue in one of the members being joined and a groove in the other member. Such a joint is widely used in joining together flooring material, wall blocks, staves and other similar construction elements.

The conventional type of building elements are costly to manufacture and difficult to handle when being assembled. The explanation of this is found in the fact that both male and female pieces are involved. Thus, for example, when wooden blocks are being formed so that they can be assembled in a unitary interlocking structure, it is necessary that half of the edges be formed into male connections and the other half formed into female connections. It will be apparent that forming two different types of connections is more costly than the formation of merely one type of connection on all ends. In all cases and particularly in the case of assembling blocks or other four-sided elements, considerable time is lost in selection and adjustment of the elements before they may be interlocked.

The need for improved interlocking building elements has been greatly increased by the advent of prefabricated housing which must be assembled with a minimum of effort and expenditure of time and yet result in strong structures. In addition, present building elements have been found inadequate for the rapid construction of many types of demonstrating models and toys.

It is, therefore, an object of this invention to provide an interlocking building element having a simplified construction and which, when assembled with other similar elements, will result in a strong structure being formed.

Another object of this invention is to provide a building element which will interlock with another building element identical to it to form a strong structure.

An additional object of this invention is to provide a building element having a joint portion which will interlock with an identically shaped joint portion of another building element.

Another object of this invention is to form

2

a building element having a plurality of interlocking joint portions, all of which will interlock with any of the joint portions on an identical building element.

5 These and other objects of this invention will become apparent upon reading the description in conjunction with the drawings, in which:

Figure 1 is a perspective view in elevation of a building block used in the formation of parallel walls;

Figure 2 is a vertical section through a pair of blocks showing them just before their adjacent sides are joined together;

Figure 3 is a side view of two parallel walls formed by blocks embodying this invention;

Figure 4 is a section taken on a plane indicated at 14—14 in Figure 3;

Figure 5 is a partial face view of a wall formed by blocks embodying this invention, showing in particular the construction of a corner;

Figure 6 is a section taken looking down on the plane indicated at 16—16 in Figure 5;

Figure 7 is a section taken looking down on the plane indicated at 17—17 in Figure 5;

25 Figure 8 is a section taken looking down on the plane indicated at 18—18 in Figure 5;

Figure 9 is a section taken looking down on the plane indicated at 19—19 in Figure 5;

Figure 10 is a section taken looking down on the plane indicated at 20—20 in Figure 5;

Figure 11 is a section taken looking down on the plane indicated at 21—21 in Figure 5; and

Figure 12 is a section taken looking down on the plane indicated at 22—22 in Figure 5.

35 In Figure 1 there is shown a block 132 embodying this invention. When assembled with other identical blocks, blocks 132 present square inner and outer faces. The block 132 has offset portions 134 and 136 having chamfered faces

40 138, 139, 140, 141, 142, 143, 144 and 145. Faces 138, 139, 142 and 143 lie in planes which are parallel. Similarly, faces 140, 141, 144 and 145 lie in parallel planes. In the portion 134 there is a keystone-shaped cut-out portion 146 suitable for the reception of a similarly shaped support member.

45 The block, if made of wood, may be formed from a piece of wood of appropriate thickness by the use of a suitable milling cutter and which will produce the desired edge formation of the block.

From the manner in which the block 132 is formed, it will be apparent that each side of the block will firmly interlock with the opposite side of an identically formed block in engagement

therewith and form a strong joint therebetween.

The manner of joining such blocks is shown in Figure 2. Blocks 2' and 2'' which are identical with block 134 are shown placed in similar positions with two adjacent sides facing and in position to be interlocked. If the blocks were pushed together, it will be noted that the faces 8' and 12' will abut against faces 16' and 20' and the surface 38 below the projecting portion 21 will be in contact with the surface 40 of block 2''. When these blocks have been thus joined, it will be noted that an extremely strong joint is formed. Thus, if, as shown in Figure 2, the right-hand end of block 2'' were tilted upwardly, the block would tend to rotate about a point approximately at 42 resulting in face 20' being forced against face 8' and face 16' being forced against face 12'. If block 2' were similarly moved in a downwardly direction, the above-mentioned faces will similarly be forced together tending to pivot this time about a point approximately at 43. The above illustration, of course, presupposes that the blocks are prevented from moving in a horizontal direction. If the blocks, as shown in Figure 2, were vertically disposed instead of horizontally disposed, it would be apparent that force of gravity would prevent the upper block from moving downwardly and no additional force would be necessary to keep the blocks together. All of the foregoing results from the fact that the salient dihedral angles of the blocks are the same as the dihedral reentrant angles of the sockets which receive them.

As shown in Figure 3, the block 132 may be used to construct two parallel walls 143 and 150 which are supported by a foundation 152 and a beam 154. In order to mutually strengthen the walls 143 and 150, a cross member 156 which has keystone-shaped ends 158 may be secured to both walls by sliding the keystone-shaped members 158 into the cut-out portions 145 of a pair of oppositely disposed blocks 132 before adding any blocks which would obstruct access to the cut-out portions 146.

In addition, Figure 3 shows a small section of roof 160 formed by the use of blocks 162 which cut in a manner similar to the cutting of block 132 but the blocks 162 are of rectangular form rather than of square form. Similarly, sections of flooring 154 are shown, this flooring being formed in a manner identical with the block 134.

Figures 5 through 12 show the invention applied to the formation and joinder of a pair of walls which are angularly disposed with respect to each other so as to form a continuous structure of great strength. It will be noted that here again offset chamfered faces providing salient and reentrant angles are utilized in a manner similar to the above described embodiments of the invention. In particular, these figures show how corner elements and base elements can be formed.

Two walls 130 which are at right angles to each other are formed principally of blocks 132. Blocks 132 are identical to the block 132 with the exception that they do not have a keystone cut-out portion for the reception of a support member. As shown, blocks 132 have offset portions 194 and 196 and chamfered faces 198, 200, 202, 204, 206, 208, 210 and 212. The faces 198, 202, 203 and 210 lie in parallel planes. Similarly faces 200, 204, 206 and 212 lie in parallel planes. The blocks are assembled to form the wall in

such manner that a vertical plane can pass through two diagonal corners of each exposed face of the block.

In order to support the lowermost blocks 192, base blocks 214 are used. Each base block 214 has a base portion 216 which fits into groove 218 in the base 220. Block 214 has upper faces 198', 200', 205' and 208' which are offset like and exact duplicates of the upper faces 198, 200, 206 and 208 of the blocks 192, and, thus interlock with the lower faces of the adjacent blocks 192.

The corner is formed by means of corner elements 222. As clearly shown in Figure 5 and Figures 7 through 12, each element 222 has chamfered faces 198'', 200'', 202'', 204'', 206'', 208'', 210'' and 212'' which are arranged to interlock with the faces of the blocks 192. The corner elements 222 are, in effect, formed by splitting in half a block like the block 192 and securing the halves thus formed to a filler member so that the exposed faces of the halves will lie in planes at right angles to each other. In practice, of course, the element 222 may be formed by cutting a suitably preshaped block with a suitable cutter.

A base corner element 224 is almost identical with corner elements 222 in that it has identical chamfered faces 200''', 202''', 206''', and 210''' and chamfered faces identical with faces 198'', 204'', 208'' and 212''. However, element 224 differs from corner element 222 in that it has, in addition, a portion 226 which projects into grooves 218 in base 220.

It will be apparent that this invention may be used in the formation of structures which utilize a plurality of interlocking elements irrespective of the shape of the elements provided that the elements may be provided with salient and reentrant angles in accordance with this invention. Thus, the elements might be curved and utilized to construct a cylindrical or other rounded structure. For example, the elements are useful in the construction of water tanks.

It should be noted that innumerable materials are suitable for use in embodiments of this invention. Thus, for example, the blocks could be cast out of cement or metal or any material having the requisite strength necessary for the structure involved. This invention has been found to be useful in building structures of plastic material particularly models and toys. In the case of elements formed out of sheet metal, it will be apparent that this invention has great utility since all of the interlocking portions of a sheet metal element may be formed by the use of the same tool.

It will be apparent that the embodiments of this invention which have been illustrated and described are merely illustrative of this invention and that numerous other embodiments are possible.

What I claim and desire to protect by Letters Patent is:

1. In a building wall a pair of spaced parallel vertical walls each comprising a plurality of interlocking building elements, said elements each being of flat form and the adjacent faces of each of the elements in a wall having a pair of salient dihedral angles and a reentrant dihedral angle between them so arranged that a salient dihedral angle of each face interlocks with the reentrant angle of the adjacent face of the adjacent element, and a strength member extending between said walls and having ends which interlock with cutout portions in two of said building elements

oppositely disposed in said parallel walls and engage the faces of the said two elements adjacent to said cutout portions.

2. In a building wall a structure including a wall comprising a plurality of interlocking building elements, said elements each being of flat rectangular form and the adjacent faces of each of the elements having a pair of salient dihedral angles and a reentrant dihedral angle between them so arranged that a salient dihedral angle of each face interlocks with the reentrant angle of the adjacent face of the adjacent angle, each of said elements being positioned in the wall with a diagonal axis extending vertically, and a vertically extending corner element presenting a 15 saw-toothed edge having edge surfaces presenting a pair of salient dihedral angles and a reentrant dihedral angle so that a salient dihedral angle of each saw-toothed face interlocks with the re-

entrant angle of the adjacent face of the adjacent element.

WILLIAM HENRICHSEN.
